UNITED STATES PATENT OFFICE.

CHARLES H. NAPIER, OF MACON, GEORGIA.

MOTOR-DRIVE FOR TARGET-THROWING MACHINES.

1,376,825.

Specification of Letters Patent.

Patented May 3, 1921.

Application filed July 6, 1920. Serial No. 394,114.

To all whom it may concern:

Be it known that I, CHARLES H. NAPIER, a citizen of the United States of America, and a resident of Macon, county of Bibb, 5 and State of Georgia, have invented certain new and useful Improvements in Motor-Drives for Target-Throwing Machines, of which the following is a specification.

This invention relates to motor driven 10 mechanism particularly suitable for energizing the driving springs of catapults of the type described in applicant's co-pending application for patent Serial No. 374,452, filed April 16, 1920.

15 The objects of the invention are to provide a suitable mechanism whereby a motor may be employed for tensioning the drive spring with sufficient rapidity to make a practical motor driven target throwing machine and to provide means for insuring the proper cyclic operation with safety devices preventing the release of the target throwing mechanism until the mechanism is properly set and also to prevent premature re- 20 setting of the mechanism.

25 The objects of the invention are accomplished by the construction shown in the accompanying drawings wherein—

Figure 1 is a side elevation of a target 30 throwing machine with a motor driven setting mechanism therefor, the latter mechanism being shown partly in section.

Fig. 2 is a plan view with the throwing mechanism omitted, but showing its sup- 35 port in section.

Fig. 3 is a detail in plan, showing the automatic mechanism for coupling of motor with said devices of the target machine.

Fig. 4 is a sectional detail taken on the 40 line 4—4 of Fig. 3.

Fig. 5 is a detail of automatic circuit controller for the trigger of the target throwing mechanism.

Fig. 6 is a perspective detail of an arm 45 forming part of the circuit opening and motor coupling mechanism.

Target throwing machines are often operated with considerable rapidity and therefore if provided with a motor drive, a com- 50 paratively strong motor is required in order to do the required work in a minimum time, but in order that the motor may be in constant operation to become effective in energizing the target throwing spring promptly 55 at the required time, it is necessary to provide carefully designed means for automatically

coupling the motor with the driven elements the instant the target throwing machine has completed an operation. It is also necessary to provide means for preventing 60 release of the target throwing mechanism until the motor has completed its work.

The devices employed for the above mentioned purposes as illustrated in the drawings, include a design of target throwing 65 mechanism comprising a driving spring 1 for oscillating an arm 2 for the link connection 3 with a target projector 4. The spring is normally retained against action by trigger 5 in latched relation with the projector 4. The trigger 5 is operated to release the target throwing mechanism by a solenoid 6, the circuit 7 of which is controlled by manually operated switch 8, and an automatic circuit controller 9 shown in 70 Fig. 5. This circuit controller is arranged to maintain the circuit open at the times that spring 1 is being placed under tension. The mechanism for tensioning spring 1 consists of a reciprocating slide 10, which at its 80 rear end is attached to a chain 11. This chain passes around pulleys 12 and 13, the opposite end of the chain being attached to a torsion spring 43 which is adapted to take up the slack of the chain on rearward motions 85 on the slide 10. The chain carries a circular knob 14 which on forward motions of the slide 10 engages an arm 15 rotatable and rigid with the arm 2. The spring 1 is linked by a chain 16 with another arm 17 also rigid 90 with arm 2. With this construction, when the slide 10 is drawn to the left, Fig. 1, the knob 14 engages the arm 15 rotating it and the elements rigid therewith to the left around pivot 18, thus tensioning spring 1 95 and drawing the projector forward to the position shown in Fig. 1, where it is latched by the trigger 5. The slide 10 may then independently move to the right, the slack of chain 11 being taken up by spring 13, the 100 knob 14 carried by the chain, moving idly away from the arm 15.

For the purpose of reciprocating the slide 10, a motor 19 is geared to reciprocate a crosshead 20, which is automatically coupled and uncoupled from slide 10 by the vertically slidable dog 21 in an aperture 22 of slide 10, and a hook-shaped element 23 rigid with the crosshead 20. The motor through the worm 24 drives a worm-wheel 25, which 105 is connected by a link 26 with crosshead 20.

When the dog 21 is in the position shown

in Fig. 4, the crosshead 20 is idly reciprocated, but when the trigger 5 is operated to release the target throwing mechanism, arm 15, Fig. 1, is rotated to the right by spring 1, far enough to come to the position of knob 14 and pull on chain 11 sufficiently to move slide 10 to the right, Fig. 4, so that the shoulders 27 engage the edges 28 of brackets 29 which support the pulley 12. This slight motion of the slide 10 causes the ends of a pin 30 carried by dog 21 to register with slots 31 in a pair of arms 32 which are pivoted at 33 to the sides of brackets 29. The dog 21 then drops into coacting relation with the hook 23 and the slide 10 is drawn to the left, thus energizing spring 1 and permitting the projector 4 to become re-latched by trigger 5. The arms 32 are cammed upwardly out of the path of pin 30 by this pin 20 engaging the inclined surfaces 34 at the edges of slots 31. Upon the return of the crosshead 20 and slide 10 which the crosshead pushes by contact at the point 35, the pin 30 rides upwardly along the inclined forward ends 36 of the arms 32, thus restoring dog 21 to the position in which it is shown in Fig. 4. When in this position it is held inoperative in respect to the hook 23 and does not again become operative until 30 the slide 10 moves slightly to the right upon release of the target throwing mechanism, as before described.

The circuit 7 can be closed only when the circuit controller 9 is in the condition shown in Fig. 5. This circuit controller comprises a pair of contacts 37 carried by a block of insulation 38 which in turn is mounted on the arms 32, so that it may rise slightly from these arms against the action of springs 39 40 encircling pins 40 carried by block 38 and passing through aperture in arms 32. When the dog 21 rides upwardly on the inclined ends 36 of the arms 32, it engages both of the contacts 37 closing the circuit. It is thus possible to energize the solenoid 6 only when the dog 21 is in the position shown in Fig. 4. After the circuit is closed, the dog moves forwardly and then drops away from the contacts 37. 50 In the operation of the device, the constantly running motor serves to reciprocate the crosshead 20 through link connection 26 with the driven worm-wheel 25. The reciprocation of crosshead 20 is idle, that is, it does not effect the motion of slide 10 except when this slide is permitted to move to the right slightly by the release of the target throwing mechanism. The target throwing mechanism is released by an action of solenoid 6, Figs. 1 and 2, upon the closing of switch 8. When the slide 10 thus moves slightly to the right, Fig. 4, dog 21 drops as permitted by the pin 30, registering with the slots 31 and comes into the position for

coacting with the hook 23. The dog 21 and slide 10 in which it is mounted, are then drawn to the left fully tensioning spring 1 and causing the projector 4 to become re-latched by trigger 5. The return reciprocation of crosshead 20 pushes the slide 10 back to the position in which it is shown in Fig. 4, the dog 21 riding up the inclined ends 36 of arms 32 at the engagement with the hook 23, but in position to close the circuit 7 at the contacts 37, Fig. 5. 75

Although but one specific embodiment of this invention is herein shown and described, it will be understood that details of the construction shown may be altered or omitted without departing from the spirit of this invention as defined by the following claims.

I claim:

1. A mechanical throwing device comprising a projector, a driving spring for the projector, a motor and connections driven by said motor for energizing said spring, electrically controlled means for releasing said projector, and automatic mechanism for rendering said means ineffective when said spring is energized a predetermined amount.

2. A mechanical throwing device comprising a projector, a driving spring for the projector, a motor and connections driven by said motor for energizing said spring, electrically controlled means for releasing the projector, and automatic mechanism for rendering said motor ineffective until said spring is deenergized.

3. A mechanical throwing device comprising a projector, a driving spring for the projector, a motor and connections driven by said motor for energizing said spring, a latching and releasing mechanism for said projector, and automatic means for rendering ineffective said connections when the spring is energized.

4. A device of the class described comprising a throwing device and a spring for operating said throwing device, a constantly driven motor, mechanism for tensioning said spring, and means for coupling the motor with said mechanism, said means being normally ineffective but arranged to be rendered effective by action of said throwing device.

5. A device of the class described, comprising a throwing device, a spring for operating said throwing device, a constantly driven motor, and normally ineffective means for coupling said motor with said spring, said means being arranged to be rendered effective by action of said throwing device.

Signed at Chicago this third day of July, 1920.

CHARLES H. NAPIER.
